DESIGN FOR A CONTAINER CLOSURE

Harold P. Brewer, Hartford, Conn., assignor, by mesne assignments, to Maison Joubert, Inc.,
New York, N. Y., a corporation of New York

Application June 22, 1936, Serial No. 63,426

Term of patent 7 years

To all whom it may concern:

Be it known that I, Harold P. Brewer, a citizen of the United States, residing at Hartford, in the county of Hartford and State of Connecticut, have invented a new, original, and ornamental Design for a Container Closure, of which the following is a specification, reference being had to the accompanying drawing.

Of the drawing:

Fig. 1 is a top view of a container closure embodying my new design.

Fig. 2 is a side view.

Fig. 3 is a combined side and sectional view, the section being taken along the line 3—3 of Fig. 1.

Fig. 4 is a combined side and sectional view, the section being taken along the line 4—4 of Fig. 1.

Fig. 5 is a fragmentary sectional view taken along the line 5—5 of Fig. 1.

I claim:

The ornamental design for a container closure as shown.

HAROLD P. BREWER.
